UNITED STATES PATENT OFFICE

WILLIAM CECIL, OF NEW YORK, N. Y.

PIPE RACK

Application filed January 21, 1933. Serial No. 652,839.

My invention relates generally to the association with a container for tobacco and the like, of a means for supporting from said container instrumentalities employing the contained material or of utility in connection therewith, such as smokers' pipes or the like, and coordinately relates to an arrangement whereby the association is attained by means which are in the form of an attachment for the container.

In the drawings herein, I have illustrated my container as intended to receive tobacco or the like, and, therefore I have illustrated my instrumentalities as smokers' pipes and pipe cleaners. The disclosure of my invention will therefore be by specific reference to a tobacco jar and associated pipe holding and pipe cleaning means.

Among the more important objects of my invention are: the provision of an arrangement whereby pipes can be supported from a container at varying elevations; the provision with a container, of pipe supporting means so devised and constructed as to be capable of supporting a variable number of pipes; the provision with a container, of pipe supporting means so devised and constructed as to be capable of adjustment for purposes of supporting the pipes in varying lateral relation about the container; the provision with a container, of pipe supporting means so devised and constructed as to be capable of supporting a variable number of pipes and of supporting the pipes at different elevations; the provision with a container, of pipe supporting means so devised and constructed as to be capable of adjustment for supporting a variable number of pipes and in varying lateral relationships of the pipes about the container; the provision with a container of pipe supporting means so devised and constructed as to be capable of supporting pipes at varying elevations in reference to the container and at adjusted lateral positions about the container; the provision with a container of pipe supporting means so devised and constructed and associated with the container as to be capable of supporting a variable number of pipes at different elevations and in varying positions of lateral relationship; the

provision of pipe supporting means as above variously characterized in the form of an attachment to a tobacco jar or container; the provision with a container, of a pipe cleaner container, associated therewith in a novel manner; the further provision with a container, of pipe supporting means which can also serve as a handle for the container.

In the embodiment herein illustrated, I show a more or less conventional type of tobacco jar and the association therewith of a pipe holder which may, if desired, be in the form of an attachment readily detachable therefrom to maintain the pipe rack in the desired or associated relation. The pipe rack is in the form of a plurality of members illustrated in the drawings as generally annular and supported from the container so as to be angularly adjustable thereabout both in reference to the container and in reference to each other. The members are illustrated as each provided with an outwardly extending flange to serve to support a pipe, as, for example, by means of an opening formed therethrough to receive the pipes therein. The flanges and the members are so constructed and related that the flanges are at different elevations so that the pipes secured to each of the flanges will also be so supported and they are further so related that the openings in the flanges when brought into and out of registration will decrease or increase the pipe carrying capacity and furthermore, when adjusted laterally of each other by relative angular movements will vary the relative lateral positions of the pipes supported by the rack.

The general object of my invention is the novel association with a tobacco jar of a new and improved pipe rack and also of means for holding pipe cleaning means.

For the attainment of these objects and such other objects as may hereinafter appear or be pointed out, I have illustrated in the drawings, certain embodiments of my invention, wherein:

Figure 1 shows in side elevation, one embodiment of my invention, parts being broken away;

Figure 2 is a top plan view of Figure 1;
Figure 3 is a perspective of Figure 1;

100

Figure 4 is a top elevational view of the container with the cover removed and with the position of parts slightly varied;

Figure 5 is a view like Figure 1 showing 5 the rack members in a position to support a plurality of pipes;

Figures 6, 7 and 8 show a further embodiment of my invention;

Figures 9 and 10 are side and top elevational views of a further embodiment; and

Figure 11 is a top plan fragmentary view of a still further embodiment.

Upon viewing Figures 1, 2 and 3 of the drawings, it will be observed that I here 15 show a generally cylindrical shaped tobacco jar 10 of a more or less conventional type and in which the bottom 11 is elevated. The member 12 is a closure member for the container also of a more or less conventional 20 type.

In order to attain all of the advantages hereinafter to be more fully referred to, I have illustrated my pipe rack in the various figures of the drawings as made up of a 25 plurality of members mounted for relative adjustment, and these members are shown in some of the embodiments as in the form of flat annuli 15, seven being shown in the embodiment of Figures 1 and 3, by way of example. These flat annuli are shown as positioned in superimposed relation to form a compact pipe rack assembly as shown clearly in Figures 1 and 3, the assembly being supported in any preferred or desired manner 30 as for example between beads 17 and 18 35 formed on the side wall of the container. The fit between each of the annuli 15 of the rack assembly and the container is such as to permit of a free rotation of the members 15 relatively to each other and to the container.

Each annulus 15 is so devised and constructed as to serve to support a pipe as for example in the manner shown in the drawings 45 in which each annulus 15 is provided with the outwardly projecting flanges 19 in which is formed the opening 20 and the openings 20 of all of the annuli are so dimensioned and related as to be capable of being brought into 50 registration for the purpose that will more fully appear hereinafter.

In Figure 1 of the drawings I have shown these members 15 as angularly adjusted so as to bring the openings 20 of all of them into 55 registration, in which position the rack assembly will serve to support a single pipe received through the registering openings 20, as for example by positioning the pipe in the manner shown in Figure 5 of the drawings, 60 that is, with the bowl on top and the stem pendant and passed through the registering openings 20. In this position of the flanges 19 and the openings 20, the assembled flanges serve usefully additionally to provide a handle member for the container in the manner 65

illustrated in Figure 3 although it will be understood that when the members are not registered as for example as shown in Figure 4, one of the flanges 19 and its associated opening 20 can be made to serve this purpose.

The pipe rack constructed as hereinabove set forth can have its elements angularly adjusted so as to vary the capacity of the rack for pipe supporting purposes, and in the illustrated embodiments where seven such elements are shown, my pipe rack can have its elements 15 adjusted so as to present support for any number of pipes from one to seven. Furthermore, due to the free angular adjustability of the members 15 with relation to each other, and to the container, any desired angular position of any single pipe supporting member 19 or of any group of members relative to the others and to the container can be attained so that the lateral relationship of the supported pipes can be varied.

By the arrangement hereinabove described, I attain the further result that due to the positioning of the members 15 in vertical relationship, a group of pipes when supported in the rack, the members of which are adjusted to the position shown for example in Figure 4, will have the individual pipes supported at different elevations and this the 95 rack herein disclosed will accommodate itself to pipes of varied length. Of course, it will be understood in connection with this feature of my invention of the varied elevation of the different supports 19, that while 100 I have illustrated its attainment by the employment of a rack assembly comprising a plurality of members adjustable as above set forth because this arrangement other advantages are also attained, nevertheless, the attainment of a difference in the elevation of the supports for the individual pipes can be attained by a plural pipe holding rack which is not in the form of an assembly of units, or if in the form of an assembly of units, 110 has its units adjustable.

In the embodiment of the invention above described the rack assembly is shown as maintained in association with the container against ready disassociation by means of the 115 beads 17 and 18. The rack need not be so associated and can be associated so as to be readily assembled and disassembled from the container in any preferred or desired manner as for example in the manner shown in 120 Figures 5, 6 and 7 of the drawings, wherein I show the top bead 17' as broken away as shown at 27 and the annuli 15' as each provided with inwardly extending projections or teats 29 so positioned and contoured that 125 by bringing the projections 29 of the members 15' into registration with the openings 27 through the bead 17', the members 15' can be removed one at a time, and in the specific embodiment of Figures 6, 7 and 8, I have 130

shown the projections 29 as duplicated on all the members 15' with reference to the position of flange 19' and the opening 20' whereby upon bringing the openings 20' into registration, the projections 29 also are brought into registration. With this assembly position of the members 15', the registering projections 29 can be brought into registration with the openings 27 through the bead 17 and the 10 rack elements 15' and can then be associated with and disassociated from the container as a unit assembly.

In the embodiments of Figures 1 to 9 inclusive, I have shown the rack elements 15 as in the form of annuli formed flat and as a stamping. It will be understood that these elements can take various embodiments. For example, in Figures 9 and 10 I show these elements as formed from material in wire 20 form, by a bending operation to provide two arms 40 and 41 arranged, constructed and dimensioned to freely encompass the container, as for example, and to be received for example between the beads 17 and 18 of Figure 1 to permit generally of the attainment of all of the objectives of the corresponding elements 15 in Figure 1. Each of these wire like members is further provided with a loop 43 formed intermediate the arms 40 and 41 to 30 serve the purposes of the flange 19 and to provide an opening 45 corresponding to the opening 20 in Figure 1. Where desired, these wire members can be made sufficiently flexible that while maintaining the rack elements 35 in assembled relation about the container, yet by the application of sufficient pressure, they can be readily removed therefrom.

While I have illustrated in each of the embodiments thus far described, the provision 40 in each of the rack elements of a single opening for supporting a pipe, it will be understood here also that the construction can be varied within limits and I have shown in Figure 11, as an example, the rack members 15" 45 received below the bead 17" as each provided with a flange 19" made sufficiently large to have provided therein two openings 20" to receive two pipes.

My invention further contemplates the association with a tobacco jar of means for holding pipe cleaners and the like and upon viewing Figure 1 of the drawings, I show for this purpose, an elongated receptacle 60 supported from the container in any preferred or desired manner, as for example, from the inside wall of the container 10 as shown in the drawings. This receptacle 60 is made of a sufficient length so as to receive pipe cleaners and the like with the ends 62 projecting 60 through the open top of the receptacle 60.

In order to properly integrate this receptacle with the tobacco container, I so dimension the receptacle 60 and so position it with reference to the container that its open top 65 is below the top of the container as shown in

the drawings, and its lower portion projects through the bottom 11 of the container.

As a result of this arrangement I am enabled to employ the space below the bottom of the container for adding to the length of the 70 receptacle 60 and thus provide sufficient length for permitting the pipe cleaners to project beyond the top of the receptacle 60 without interfering with the cover.

The cover member 12 has been shaped as 75 shown in Figure 1 so as to receive and hold a moistening element, such as a sponge, shown at 70 in this figure.

In the various embodiments I have illustrated the pipes as supported bowl up, although it will be understood that they can be supported bowl down, as for example, by slightly widening the base of container 10 and properly contouring this base for this purpose. So also, I have shown the pipe stems 80 as received through the openings in the flanges 19, 19', 19" although upon viewing Figures 4 and 7 of the drawings, it will be observed that the stems can be received between these flanges and with the bowls either 85 up or down.

Therefore, while I have illustrated and described certain specific embodiments of my invention it will be understood that the scope of my invention is not to be restricted to such 90 embodiments either as to dimensions or contours or manner of use or otherwise, unless such restrictions are necessarily called for by the language of the claims.

Having thus described my invention and 100 illustrated its use, what I claim as new and desire to secure by Letters Patent, is:

1. A pipe supporting attachment for a tobacco jar comprising a plurality of units in assembled relation, each unit comprising 105 means adapted to secure it to the tobacco jar so that the units are capable of relative adjustment relatively to each other and to the tobacco jar, each unit comprising additionally means for supporting a pipe so devised and constructed that as the units are relatively adjusted, the pipe supporting means may be varied positionally relatively to each other and to the tobacco jar and the pipe supporting capacity of the assembly increased or decreased.

2. A pipe supporting attachment for a tobacco jar comprising a plurality of units in assembled relation, each unit comprising 115 means adapted to secure it to the tobacco jar so that the units are capable of relative adjustment relatively to each other and to the tobacco jar, each unit comprising additionally means for supporting a pipe so devised and constructed that as the units are relatively adjusted, the pipe supporting means may be varied positionally relatively to each other and to the tobacco jar and the pipe supporting capacity of the assembly increased or decreased, the pipe supporting 120 125 130

means of the various units being so related as to support pipes at different elevations.

3. A pipe supporting attachment for a tobacco jar comprising a plurality of units in assembled relation each unit comprising means adapted to secure it to the tobacco jar for adjustment of said unit about the tobacco jar, and each unit also comprising laterally extending means having an opening there-
10 through for supporting a pipe by means of the bowl with the stem extending downwardly through the opening, the units being adapted to be supported about the jar with said laterally extending means at different elevations whereby the pipes will be supported at different elevations and whereby the units can be adjusted to bring two or more of the aforementioned openings into vertical relation so as to reduce the pipe
15 carrying capacity of the assembly.

4. A pipe supporting attachment for a tobacco jar comprising a plurality of units in assembled relation each unit comprising a ring embracing the jar and laterally ex-
20 tending means having an opening there-
through for supporting a pipe by means of the bowl with the stem extending downwardly through the opening, the units being adapted to be supported about the jar with
25 the rings in superimposed relation with said laterally extending means at different elevations whereby the pipes will be supported at different elevations and whereby the units can be adjusted to bring two or more of the
30 aforementioned openings into vertical relation so as to reduce the pipe carrying capacity of the assembly.

5. A pipe supporting attachment for a tobacco jar comprising a plurality of units
40 in assembled relation each unit comprising a ring embracing the jar and laterally ex-
tending means having an opening there-
through for supporting a pipe by means of the bowl with the stem extending down-
45 wardly through the opening, the units being adapted to be supported about the jar with the rings in superimposed relation with said laterally extending means at different elevations whereby the pipes will be supported at
50 different elevations and whereby the units can be adjusted to bring two or more of the aforementioned openings into vertical relation so as to reduce the pipe carrying capacity
55 of the assembly and means for maintaining said rings from moving vertically.

In witness whereof I have hereunto signed my name.

WILLIAM CECIL.
